AERIAL TRAMWAYS

Ernest George Tiegel, 1561 County Road,
Redwood City, Calif.

Filed Apr. 18, 1955, Ser. No. 502,053

2 Claims. (Cl. 104—178)

The present invention relates to improvements in aerial tramways, and has particular reference to a ski lift, although the principles involved apply to any apparatus in which a cable is trained over a pair of spaced, horizontally disposed sheaves, and is made to carry a load around the sheave.

In a ski lift, the load, such as a passenger seat, usually is suspended from the cable by means of a vertical hanger, and one of the most limiting factors controlling the maximum speed of the cable is the fact that in passing around the sheave the hanger is made to swing outward by centrifugal force, and keeps swinging back and forth, even after rounding the sheave.

Different attempts have been made to eliminate this outward swing and the most widely used one is to provide an outer guide rail around the sheave. While this prevents outward swing, the friction of the hanger against the fixed guide causes the bucket to drag behind, and there is considerable back and forth swing when the cable straightens out after leaving the sheave.

It has also been proposed to eliminate the swing by arranging a stop plate on the sheave to overlie the hanger head, so as to hold the latter against upward tilt. In this instance, however, there again is considerable friction which is detrimental to the cable, the hanger head and the sheave, and does not stop the swinging movement altogether.

In the present invention, it is proposed to provide a simple solution for the problem of guiding the hanger around the sheave, which avoids all friction and binding while preventing outward play due to centrifugal force.

More particularly, it is proposed to provide guide means for the hanger which move with the hanger in its course around the sheave, one of the guide means being a ring which rotates with the sheave and engages the inner face of the hanger, and the other being an endless belt having a section trained over the ring, so as to engage the outer face of the hanger and to urge the latter upon the ring, both the ring and the belt moving at the same speed as the sheave, and the belt being driven by the ring.

It is further proposed to train the belt in such a way that it provides entry and exit approaches for the hanger to guide the latter toward and away from the ring, in combination with cooperating fixed approaches mounted opposite the belt approaches.

Further objects and advantages of my invention will be apparent as the specification continues, and the new and useful features of my invention will be fully defined in the claims forming part of this application.

The preferred form of my invention is illustrated in the accompanying drawing, forming part of this application in which:

Figure 1 shows a vertical axial section through the terminal tower of a ski lift;

Figure 2, a horizontal section taken along line 2—2 of Figure 1; and

2

Figure 3, an enlarged detail view showing a hanger head and attendant structure.

While I have shown only the preferred form of my invention, it should be understood that various changes or modifications may be made within the scope of the claims hereto attached, without departing from the spirit of the invention.

Referring to the drawing in detail, Figure 1 shows, somewhat schematically, a terminal station, including 10 a tower 1 having a sheave 2 revolvably mounted upon the top thereof, the sheave being rotated by any suitable means, not shown.

A cable 3 is guided around one-half of the sheave, the cable being endless, and being trained around a 15 second sheave of a second terminal disposed at a distance from the first terminal.

The cable has a series of buckets 4 suspended therefrom by means of rigid hangers 5, and hanger heads indicated at 6. The hanger heads may be of conventional 20 construction and each comprises a pair of brackets 7 clamped upon the cable, as by bolts 8, and projecting sideways of the cable to form the bearings 9 for the upper end of the hanger.

Each hanger is curved inwardly, as at 10, to bring 25 the bucket 4 vertically underneath the rim of the sheave over which the cable travels.

As each hanger travels around the sheave, its bucket develops a definite tendency to swing away from the axis of rotation, due to centrifugal force, and it is the 30 object of the present invention to prevent such outward swing without causing undue friction and binding action.

For this purpose, I provide a ring 11 suspended from the sheave 2 by means of brackets 12, and made to rotate with the sheave. The diameter of the ring 11 is such 35 that the circumference of the ring naturally makes contact with the inner edge of a freely suspended hanger.

The ring thus serves as a natural guide for the hanger, rotating at the same speed as the latter.

Each hanger is held to the ring by means of a belt 40 13, which may be in the form of a cable or rope, and an intermediate section of which, shown at 14, is guided around the outer or driving face 15 of the ring.

The remainder of the belt is guided over four pulleys 16, 17, 18 and 19, the pulleys being arranged substantially in the four corners of a rectangle in such a manner 45 that the pulley 16 feeds the belt to the driving face of the ring 11, while the driving face feeds to the pulley 19, which latter reverses the direction of the belt to pass over pulleys 18 and 17, back to pulley 16.

In this manner, the intermediate reversely curved portion 14 of the belt is driven continuously by the driving face of the ring and bears on the outer face of the hanger 5, urging the latter upon the ring, and preventing the hanger from swinging outward.

Since the ring and the belt and the sheave all rotate 55 at the same speed, there is no friction between the hanger and the ring, or between the hanger and the belt, and the hanger is made to move around the ring and the sheave smoothly, while maintaining its vertical position.

In the horizontal section shown in Figure 2, the general 60 path of each hanger is indicated by the dash and dot line 21, and it will be noted that the stretch 22 of the belt between the pulley 16 and the ring 11 runs almost parallel to the travel of the hanger so as to smoothly engage over the outer face of the hanger as the latter 65 approaches the active face of the ring.

A slightly curved fixed guide 23 may be provided opposite the belt approach 22 to guide the hanger into contact with the belt approach.

The same arrangement is shown at the exit of the 70 hanger, where it is guided by the belt section 24 between the active face of the ring 11 and the pulley 19, and

gradually loses contact with the latter, a fixed guide 25 aiding in the transfer from circumferential to straight forward movement.

The operation of my invention will be readily understood from the foregoing description.

Referring particularly to Figure 2, as the hanger 5 of the bucket 4 approaches the sheave along the path defined by the dot-and-dash line 21, it is gradually engaged on the outside by the belt stretch 22, and on the inside, by the guide 23, which latter barely touches the hanger, but aids in guiding the latter into the space between the belt and the ring 11.

Upon entering the said space, the hanger, causing a slight outward bend in the belt, is guided by the latter and the ring, at its own natural speed, so as to pass around the ring without any outward swinging movement and still without any frictional resistance to its forward movement.

After passing around the active portion of the ring, the hanger gradually loses contact with the belt section 24 and follows its straight path toward the sheave at the opposite end.

It would, of course, be perfectly feasible, to substitute a belt similar to the one described for the two fixed guides 23 and 25, such belt being trained around the ring 11 and being made to pass over pulleys corresponding substantially to pulleys 16 and 19, so that the belt would move at the same circumferential speed as the belt 13, and would guide the inner faces of the hangers.

It is apparent that my invention applies generally to the drive station, as well as to the idler station in a ski lift, or similar tramway.

The present invention would also be useful in connection with an aerial tramway which has a bend in the line, since the U-shaped arrangement of the belt might be readily spread to conform to hanger travel approaching and departing at angles different from those indicated by the lines 21.

I claim:

1. In an aerial tramway, a horizontally mounted rotary sheave, an endless cable guided over a section thereof, a hanger suspended from the cable for movement around the sheave, and means for holding the hanger against outward swing due to centrifugal force when passing around

the sheave, the said means comprising a ring suspended from the sheave for rotation therewith about a common axis and dimensioned for engagement by the inner face of the hanger, and a belt having a series of supporting rollers arranged so as to train a section of the belt over the ring on the outside of the hanger and to urge the hanger upon the ring, the rollers being mounted to provide belt stretches approaching the ring in substantially parallel relation to the path of hanger travel.

2. In an aerial tramway, a horizontally mounted rotary sheave, an endless cable guided over a section thereof, a hanger suspended from the cable for movement around the sheave, and means for holding the hanger against outward swing due to centrifugal force when passing around the sheave, the said means comprising a ring suspended from the sheave for rotation therewith about a common axis and dimensioned for engagement by the inner face of the hanger, and a belt having a series of supporting rollers arranged in a rectangle enclosing said ring and in the plane thereof so as to train a section of the belt over the ring on the outside of the hanger and to urge the hanger upon the ring, two of said rollers being positioned with their peripheries substantially tangent to the path of said hanger as it approaches and retreats from said sheaves so as to provide belt stretches in substantially parallel relation to the path of hanger travel, and fixed guides at the ring side of said belt stretches for guiding said hangers along a path tangent to said ring.
